HYDROGENATION OF PRESSURE TAR

Robert E. Wilson, Chicago, Ill., assignor to Standard Oil Company (Indiana), Chicago, Ill., a corporation of Indiana

Application May 21, 1930, Serial No. 454,244

7 Claims. (Cl. 196—53)

This invention relates to the formation of gasoline by the hydrogenation of heavy hydrocarbon oils, and especially those of high coke forming tendencies, such as reduced "pressure tar".

5 "Pressure tar" is obtained in oil refineries as a byproduct from cracking processes which are carried out under pressure. When this heavy oil or tar is heated to temperatures high enough for hydrogenation, coke or carbon very quickly deposits 10 on the walls of the heater, in valves and return bends, etc. This carbon formation or "coking" is detrimental because it cuts down the effective heat transfer, impairs the circulation, and frequently necessitates a shut-down for cleaning. 15 While the presence of hydrogen under high pressure tends to prevent coke deposition, stocks like pressure tar have been so highly cracked and are so prone to deposit coke, that coke deposition takes place before the stocks have an opportunity 20 to be hydrogenated. The object of my invention is to provide a system for hydrogenating pressure tar and similar coke forming oils which will avoid the deposition of carbon in the tubes or other parts of the system.

25 In my improved system I heat the pressure tar to a temperature of about 650 to 750° F. (below coking temperature) in an elongated, closed conduit, and I simultaneously heat a non-coking liquid to a temperature of about 850 to 950° F. I 30 then mix the hot pressure tar with the other heated liquid in such proportions that the resulting temperature is from 750 to 850° F., the temperature depending upon the nature of the catalyst, the nature of the charging stock, and 35 the desired end product. Since the temperature of the pressure tar is below coking, there will be no deposition of carbon in these tubes. As a further safeguard, I increase the velocity and turbulence in the pressure tar heater by mixing 40 more hydrogen with the pressure tar than with the clean charging stock. By regulating the amounts of different charging stocks and simultaneously regulating the amount of hydrogen introduced into each charging stock and the temperatures to which charging stocks are heated, I 45 can effectively eliminate coking in the pipe still, and yet bring the pressure tar to the desired temperature for hydrogenation.

The non-coking liquid used may suitably be a 50 light stock as light gas oil or naphtha bottoms, or a heavy, slow cracking distillate stock such as pressure tar distillate. The atomic ratio of hydrogen to carbon is an index of the tendency to coke or deposit carbon. A clean stock, one which 55 has no appreciable tendency to coke, has a hy-

drogen:carbon ratio of about 1.7 to 1.85; examples of clean stocks are Mid-Continent crude with a ratio of 1.84, 37° Bé. gas oil with a ratio of 1.86, 60% reduced Mid-Continent crude with a ratio of 1.75, and pressure tar distillate with a 60 ratio of 1.69. Reduced pressure tar is an example of an oil with a tendency to coke, and its atomic hydrogen:carbon ratio is about 1.10 to 1.45.

In the accompanying drawing I have shown diagrammatically a system for carrying out my 65 invention.

Pressure tar from storage tank 10 is passed through pipe 11, pressure pump 12, pipe 13, mixer 14, heat exchanger 15 and pipe 16 to the heating coils 17 of pipe still 18, the hot fluid being discharged through pipe 19 into the base of catalyst chamber 20. Simultaneously, a clean charging stock, such as gas oil, is taken from storage tank 21 through pipe 22, pressure pump 23, pipe 24, mixer 25, heat exchanger 26, and pipe 27 to heating coils 28 of pipe still 29, the heated mixture being discharged through pipe 31, mixed with the contents of pipe 19, and discharged in the base of catalyst chamber 20.

70 The catalyst chamber may be an elongated, cylindrical vessel containing a catalyst 31 held on screens or trays 32. The catalyst is preferably a metal or an oxide of a metal of the sixth group of the periodic system, or mixtures of such metals and/or oxides; for example, nine parts of chromium oxide and one part of molybdenum oxide. Such catalysts are not poisoned by sulfur and are suitably classified as sulfactive hydrogenation catalysts. The catalyst may be supported in any conventional way, and may be held on a plurality of trays, or even circulated by the liquid if the conditions are such that the fluids in the reaction chamber are in the liquid phase.

75 Hydrogen and reaction products from the catalyst chamber are conducted by pipe 33 through pipes 34 and 35 to heat exchangers 15 and 26 in amounts regulated by valves 36 and 37. I prefer to use separate heat exchangers because the pressure tar may be heated to a lesser degree at this point and it may also be mixed with an unusually 80 large amount of hydrogen, as will be hereinafter pointed out. The reaction products leave the heat exchangers by pipes 38 and 39, and are then cooled in condenser coil 40 which liquefies gasoline and heavier hydrocarbons. The condenser coil may 85 be immersed in a suitable cooling fluid held by tank 41, the cooling fluid being introduced and withdrawn by pipes 42.

90 The cooled liquids are discharged by pipe 43 into liquid separator 44, where condensed liquids 95

110

- 45 are separated out and removed by pipe 46 through reducing valve 47.
- The gases from separating tank 44 are conducted by pipe 48 to the base of scrubber tower 49, 5 which may be filled by packing material 50 held by screen 51. The liquid 52, which is circulated in the scrubbing tower, collects in the base thereof and is withdrawn by pipe 53 through reducing valve 54 into a gas release tank 55, the gases, such as hydrogen sulfide, methane, etc. being discharged through pipe 56. The liquid from the base of gas release tank 55 is circulated through pipe 57 by high pressure pump 58, which forces it through pipe 59 and nozzle 60. This nozzle 15 sprays the liquid onto the packing material countercurrent to the upward flow of gases, which purifies the hydrogen for further use in the system. The scrubbing liquid is preferably an absorptive, nonvolatile oil.
- 20 The hydrogen leaving scrubber 49 by pipe 61 is compressed to 200 atmospheres by compressor 62. It is then mixed in pipe 63 with make-up hydrogen from high pressure line 64 in amounts regulated by valve 65. The compressed hydrogen 25 is introduced through pipe 66 into the pressure tar charging stock, and is simultaneously introduced through pipe 67 into the gas oil charging stock, the relative amounts of hydrogen being regulated by valves 68 and 69, respectively.
- 30 The operation of my invention will be obvious from the above description. A larger amount of hydrogen is preferably mixed with the pressure tar than is mixed with the gas oil because this produces a more turbulent and more rapid flow 35 of the pressure tar through the exchanger and through the pipe still, thereby minimizing the danger of coke formation in the pipes.
- The pressure tar is heated in pipe still 18 to a 40 temperature below that at which coking occurs, that is, to about 650 to 750° F. Simultaneously, the clean charging stock is heated in pipe still 29 to a temperature of about 850 to 950° F. so that the mixture will have a temperature of about 750 to 850° F. I thus avoid high temperatures in the 45 pressure tar pipe still and at the same time I supply the heat necessary for cracking and hydrogenating this material in the catalyst chamber. Coke deposition may be substantially retarded either by using a lower temperature in pipe 50 still 18 or by increasing the amount of hydrogen which is mixed with the pressure tar and thereby increasing its velocity through the pipe still. I prefer to combine these expedients and avoid all possible coking trouble.
- 55 While I have described a preferred embodiment of my invention, it is understood that I do not limit myself to the details therein set forth except as defined by the following claims.

60

65

70

75

Wherever the terms "hydrogenation" or "hydrogenating" are used herein they shall be understood to refer to processes of so-called destructive hydrogenation in which hydrocarbon materials are treated in the presence of hydrogen at elevated temperatures and high pressures with or without catalysts, said conditions being such as to result not merely in simple hydrogenation of unsaturated molecules to produce saturated ones, but in deep-seated transformations including changes in molecular weight, etc., said conditions being characterized by temperatures above 700° F. and pressures above 1,000 lbs. per sq. in.

I claim:

1. An improved method for hydrogenating and converting into lighter hydrocarbons highly cracked oils, tars and the like having a marked tendency to coke which comprises heating a stream of such oil with free hydrogen under pressure sufficiently to effect destructive hydrogenation to a temperature of 650 to 750° F., separately heating a second stream of a separate clean oil of less tendency to coke to a temperature of 850 to 950° F. under the same pressure and discharging both oils together into the destructive hydrogenation zone maintained under the same pressure and a conversion temperature. 90
2. Method according to claim 1 in which both oils are heated in contact with hydrogen under pressure. 100
3. In a continuous process for converting hydrocarbon oil tar into gasoline by subjecting said tar to the action of hydrogen at a pressure of the order of 200 atmospheres and at a thermal decomposition temperature, an improved method of operation comprising heating a stream of said tar and hydrogen at said pressure to a temperature above about 650° F. and below that at which coking is pronounced, separately heating a stream of a lighter oil having less tendency to coke and hydrogen to a temperature of about 850 to 950° F., discharging both preheated streams into a reaction zone maintained at a temperature of about 750 to 850° F. and a pressure of about 200 atmospheres and withdrawing a product comprising gasoline from said reaction zone. 110
4. Process according to claim 3 in which the tar is derived from the products of cracking of petroleum oils. 115
5. Process according to claim 3 in which the reaction zone contains a hydrogenation catalyst. 120
6. Process according to claim 3 in which the reaction zone contains a sulfactive hydrogenation catalyst. 125
7. Process according to claim 3 in which the reaction zone contains a sulfactive hydrogenation catalyst. 130

ROBERT E. WILSON.
